CLAIM

The ornamental design for a sensor housing, as shown and described.

DESCRIPTION

FIG. 1 is a front, top and left side perspective view of a sensor housing showing our new design;

FIG. 2 is a rear, top and right side perspective view of the sensor housing of FIG. 1;

FIG. 3 is a front, bottom and right side perspective view of the sensor housing of FIG. 1;

FIG. 4 is a front view of the sensor housing of FIG. 1;

FIG. 5 is a rear view of the sensor housing of FIG. 1;

FIG. 6 is a left side view of the sensor housing of FIG. 1;

FIG. 7 is a right side view of the sensor housing of FIG. 1;

FIG. 8 is a top plan view of the sensor housing of FIG. 1; and,

FIG. 9 is a bottom plan view of the sensor housing of FIG. 1.
